[57] CLAIM

The ornamental design for a toy puzzle, as shown and described.

DESCRIPTION

FIG. 1 is a top plan view of a toy puzzle showing my new design;

FIG. 2 is a front elevational view thereof, the sides opposite being substantially the same;

FIG. 3 is a bottom plan view thereof;

FIG. 4 is a side elevational view thereof, shown partially in cross-section and with some of the puzzle parts shown in an exploded condition;

FIG. 5 is a top plan view of one of the component members;

FIG. 6 is a top plan view of one of the component members;

FIG. 7 is a top plan view of one of the component members;

FIG. 8 is a top plan view of one of the component members.
